UNITED STATES PATENT OFFICE.

VINCENT PERCY SMITH, OF GILLINGHAM, ENGLAND.

ANCHOR.

1,081,163.

Specification of Letters Patent.

Patented Dec. 9, 1913.

Application filed February 5, 1913. Serial No. 746,268.

To all whom it may concern:

Be it known that I, VINCENT PERCY SMITH, a subject of the King of Great Britain and Ireland, and residing at Portland Lodge, Gillingham avenue, Gillingham, in the county of Kent, England, captain, R. A., have invented new and useful Improvements in Anchors, of which the following is a specification.

10 This invention relates to improvements in anchors and more especially to those of the mushroom or disk type.

It is well known that, while such anchors as at present constructed are not so liable 15 to become entangled in the chain, ropes or moorings, as are those having a stock, arms and flukes, yet they are not nearly so suitable as the latter class when used on a hard bottom as there are no sharp points to catch 20 in the ground.

Now according to the present invention I provide an anchor of the mushroom type having two or more points and I also eccentrically mount or load the base plate or disk 25 thereof so that the said points will be always tending to point in a downward direction.

My invention is hereinafter described with reference to, and illustrated in the accompanying drawings, in which:

30 Figure 1 is a sectional front elevation; Fig. 2 is an underside plan view; Fig. 3 is a side elevation, and Figs. 4, 5, 6, 7 and 8 are detail sectional views taken on the lines 4—4, 5—5, 6—6, 7—7, and 8—8 respectively 35 on Fig. 1.

As shown the disk or base plate *a* of the anchor has a notch or open portion *b* therein extending for about one sixth part of its circumference so as to form the points *c c* 40 which are suitably bent as shown in Figs. 2 and 3 to form flukes and which may be reinforced by forming projections or ribs thereon.

The eccentric loading may as shown in 45 Figs. 1 and 3 be effected in several ways such as by attaching the shank *d* to the base

plate *a* out of its center toward the notch *b* and points *c c*. This may also be effected by eccentrically loading the shank itself, or as shown by loading a portion of the disk 50 such as by the provision of a block *f*, or by a combination of such arrangements. The loading of the disk may if desired and as shown be accomplished or aided by the provision of apertures *e e* made in one portion 55 of the disk which reduce the weight on that side. The shank *d* may conveniently be secured to the disk *a* by means of a taper key *g* of the kind shown or in any other convenient manner. Thus I am enabled to provide 60 a stockless anchor which is easy to stow away and handle, is not liable to foul the chains, ropes, or moorings, and is suitable for use on any kind of ground or bottom.

Having now particularly described and 65 ascertained the nature of my said invention and in what manner the same is to be performed, I declare that what I claim is:

1. An anchor comprising, a substantially circular disk or head having points or flukes 70 thereon at one side thereof, and a shank attached eccentrically to the disk in the manner and for the purpose described.

2. An anchor comprising, a substantially circular disk or head having points or flukes 75 thereon at one side thereof, and a weight or block forming a boss for the reception of a shank and for effecting the eccentric loading of the disk, substantially as described.

3. An anchor comprising in combination, 80 a substantially circular disk or head having points or flukes thereon at one side thereof and provided with apertures serving to lighten the disk on the opposite side to that at which the points are formed, and a shank 85 eccentrically attached to the disk, substantially as described.

Dated this 6th day of January 1913.

VINCENT PERCY SMITH.
